UNITED STATES PATENT OFFICE.

ARTHUR J. HALL, OF WILKINSBURG, PENNSYLVANIA, ASSIGNOR TO WESTINGHOUSE ELECTRIC AND MANUFACTURING COMPANY, A CORPORATION OF PENNSYLVANIA.

CONTROL SYSTEM.

1,278,917.

Specification of Letters Patent. Patented Sept. 17, 1918.

Application filed December 10, 1914. Serial No. 876,484.

To all whom it may concern:

Be it known that I, ARTHUR J. HALL, a subject of the King of Great Britain, and a resident of Wilkinsburg, in the county of Allegheny and State of Pennsylvania, have invented a new and useful Improvement in Control Systems, of which the following is a specification.

My invention relates to control systems of the remote-control, multiple-unit type, and it has special reference to such systems as are adapted to govern the operation of fluid-actuated mechanisms.

One of the objects of my invention is to provide a simple and effective means for remotely controlling the operation of fluid-actuated devices which may be employed either to govern the operation of electrically propelled vehicles, or for any other purpose in which it is desired to actuate a member in opposite directions and to arrest its movement in any position.

Another object of my invention is to provide simple and reliable means for controlling the operation of fluid-actuated mechanisms in such manner that different rates of movement thereof may be effected in either direction of operation, at the will of the operator.

In a co-pending application, Serial No. 847,858, filed June 29, 1914, by K. A. Simmon and A. J. Hall and assigned to the Westinghouse Electric & Manufacturing Company, a control system of this general type is disclosed, which embodies an operating cylinder having a movable piston contained therein and provided with a valve in each end of the cylinder for governing the admission and release of operating fluid to and from the respective ends thereof, by means of which the piston is actuated in either direction or is held stationary in any intermediate position. When pressure is admitted at one end of the cylinder and released from the other, the piston is moved by reason of the unbalanced pressure conditions acting upon it. However, when both ends of the cylinder are supplied with operating fluid, balanced pressures exist and movements of the piston are prevented.

Assuming balanced pressure relations, movement in either direction may be effected by reducing the fluid pressure on one side of the piston by means of one of the valves, although it has been found by experience

that, with the apparatus set forth in the co-pending application referred to, there is an appreciable and undesirable time interval between the manipulation of the valve and the resulting movement of the piston. 60

In control systems that are adapted to govern the operation of electric locomotives or other electrically propelled vehicles or, in fact, many other classes of apparatus, it is important to avoid sluggishness in the mechanisms of the control system and to employ a mechanism which is sensitive, quickly-responsive and positive in operation.

Accordingly, I propose to provide each end of the operating cylinder with an auxiliary exhaust valve having, a relatively large port and to utilize the one or the other of said auxiliary valves, together with the usual main exhaust valve, for obtaining a rapid reduction in pressure on one side of the piston, whereby the operation of the fluid-actuated device is rendered quickly-responsive to the manipulation of the control means by the operator. 70

After the movement of the piston is initiated, the auxiliary exhaust valve may be allowed to close, thereby retarding the rate of operation of the system and providing a relatively slow movement of the apparatus for regulating purposes. 80

More specifically stated, I propose to provide a system for governing the operation of a railway vehicle driven by a polyphase induction motor, that is controlled by a fluid-actuated liquid rheostat having a single movable combined discharge and regulating valve, such as set forth in my co-pending application, Serial No. 873,919, filed Nov. 25, 1914, the operation of which is governed by electrically operated and controlled valves in accordance with the manipulation of a master controller. 90

Moreover, means is provided, not only for effecting a quick initial movement of the operating mechanism and combined discharge and regulating valve, but, also through the agency of a pneumatic interlocking device, a quick response to the manipulation of the master controller is insured at all times. 100

In its broadest aspect, however, my invention is not restricted to any particular type of remote-control means and may be embodied either in a system which is electrically governed through the agency of a mas- 110

ter controller and suitable circuit connections, or one which employs mechanical means of the class which includes operating levers or handles, bell cranks and interconnected actuating rods, or in one involving the use of any other means for remotely manipulating the valves of the fluid-pressure mechanism.

My invention may best be understood by reference to the accompanying drawings, in which Figure 1 is a diagrammatic view of an electrically controlled system embodying my invention; Fig. 2 is a similar view of a mechanically operated remote-control system arranged in accordance with my invention; Fig. 3 is a diagrammatic view of the main circuits and main control apparatus of a modified system embodying my invention and adapted to control the operation of an electric motor by means of a liquid rheostat, and Fig. 4 is a diagrammatic view of the auxiliary control circuits and apparatus employed for governing the main-circuit connections and apparatus shown in Fig. 3.

Referring to Fig. 1 of the drawings, the system shown comprises a movable valve 1 which is adapted to open and close a communication through a pipe 2 which may carry fluid, such as water or steam, for any of a variety of purposes, the valve 1 being associated with a fluid-actuated operating mechanism OM comprising a cylinder 4 and a movable piston 5 contained therein. The upper end of the cylinder 4 is provided with a plurality of electrically operated magnet-valves "Off-slow" and "Off-fast", while the lower end of the cylinder has associated therewith a plurality of magnet-valves "On-slow", "On-fast", for the purpose of governing the admission and release of operating fluid from a suitable source (not shown) to and from the respective ends of the cylinder 4. The valve "Off-slow", when deenergized, is normally adapted to admit operating fluid to the cylinder 4 through an inlet port 6 and to close its exhaust port 7 which has a restricted opening 7^a to the atmosphere. The valve "Off-fast" merely embodies an exhaust port 8 which is normally closed and has a relatively large opening 8^a to the atmosphere. The "On-slow" valve is normally held in its closed position, so far as its inlet port 9 is concerned, although its exhaust port 10 is opened to permit the escape of any operating fluid within the cylinder 4, through a restricted opening 10^a. Referring now to the valve "On-fast", it is provided with a normally opened exhaust port 11 which communicates with the atmosphere through an opening 11^a of material size.

Under the conditions shown in the figure and just described, fluid pressure is admitted to the upper end of the cylinder 4, while the lower end thereof is opened to the atmos-

sphere, whereby an unbalanced pressure acts upon the piston 5 and biases the same to its lowermost position.

In order to govern the operation of the several electrically controlled valves hereinbefore mentioned, a master controller MC is provided, which embodies a plurality of contact terminals 13, 14, 15, 16 and 17 and a coöperating movable conducting segment 18 which is adapted to engage the terminals in a plurality of positions marked *a*, *b*, *c*, and *d*. Positions *c* and *d* are adapted to effect an upward movement of the piston 5 and the opening of the valve 1, respectively, at a slow and at a fast rate; position *b* arranges the circuit connections for arresting any movement of the piston 5 and holding it and the valve 1 in any position; position *a* serves to cause the piston 5 and valve 1 to be lowered or closed at a slow rate, while the "Off" position of the controller effects the lowering of the piston 5 and closure of valve 1 at a fast rate.

In order to adapt the system for multiple-unit operation, whereby a plurality of operating mechanisms may be concurrently and correspondingly regulated, a plurality of so-called "Train lines" are employed, which conductors correspond in function to the well-known train-line conductors of railway control systems.

Assuming the apparatus and circuit connections to be as shown in Fig. 1, the operation of the system is as follows: If it is desired to open the valve 1 at a relatively rapid rate, the conducting segment 18 of the master controller MC is moved into its position *d*, in which a circuit is established from one terminal of an auxiliary source of energy or battery B through terminal 13, and conducting segment 18, and thence through a plurality of circuits respectively including contact terminal 14 and the energizing coil of magnet valve "Off-fast", contact terminal 15 and energizing coil of magnet valve "Off-slow", contact terminal 16 and energizing coil of magnet valve "On-slow", and contact terminal 17 and energizing coil of valve magnet "On-fast". Thus, all of the magnet valves are energized and each is moved into its opposite position. The exhaust port 10 of the valve "On-slow" is closed and its inlet port 9 is opened to admit operating fluid to the lower end of the cylinder 4, while the exhaust port 11 of the magnet valve "On-fast" is closed. Moreover, the valve "Off-slow" is actuated to close its inlet port 6 and to open its exhaust port 7, while the "Off-fast" valve is actuated to open its exhaust port 8. By reason of opening the exhaust ports of both of the magnet valves "Off-slow" and "Off-fast", it is evident that the operating fluid contained within the upper end of the cylinder is permitted to escape to the atmosphere at a rapid rate and,

therefore, a prompt response and upward movement of the piston 5 are effected at a correspondingly rapid rate.

If it is desired to reduce the speed of the opening operation, it is only necessary to move the master controller MC into its position *c* in which contact terminal 14 disengages the conducting segment 18, and the valve "Off-fast" is deenergized and permitted to close its large exhaust port 8. Thus, the release of operating fluid from the upper end of the cylinder 4 is retarded, and a correspondingly slower speed of operation is secured.

15 In case it is desired to arrest the upward movement of the valve 1 at any intermediate position, it becomes necessary to cause the conducting segment 18 of the master controller MC to occupy its position *b*, in which contact terminal 15 also becomes disengaged from the conducting segment 18, thus deenergizing the magnet valve "Off-slow." This valve, therefore, is permitted to return to its initial position in which its outlet 20 port 7 is closed and its inlet port 6 is opened. Thereupon, operating fluid is admitted to the upper end of the operating cylinder 4 to balance the pressure in the lower end thereof and to hold the piston 5 at rest in 25 whatever position it occupies.

30 The valve 1 may be lowered or closed at a slow rate by moving the master controller MC into its *a* position, whereby the disengagement of contact terminal 16 and contact segment 18 is effected and valve magnet "On-slow" is also deenergized to permit the opening of exhaust port 10 and the closure of inlet port 9. The fluid pressure beneath the piston 5, therefore, is exhausted 35 through the small port 10 and, consequently, the piston 5 is moved to close the valve 1 at a slow rate.

40 A rapid rate of closure may be obtained by moving the master controller MC to its "Off" position in which the conducting segment 18 becomes disengaged from all of the contact terminals and, therefore, all of the magnet valves are deenergized and are moved into their initial positions. Under 45 these circumstances, operating fluid is admitted above the piston 5, while both of the exhaust ports 10 and 11 of the respective valves "On-slow" and "On-fast" are opened, whereby the lower end of the cylinder 4 is 50 quickly exhausted, and a correspondingly rapid movement of the piston 5 and associated valve 1 results.

Without further description, it is evident that the piston 5 may be actuated in either 55 direction at different rates of movement or may be held stationary in any position merely by manipulating the master controller MC to its proper position.

While I find it particularly convenient 60 and advantageous to employ electrical means

for controlling the operation of the fluid-operated mechanism OM, I also contemplate effecting the control thereof through the agency of mechanical remote-control means, and, in Fig. 2 I have illustrated means of 70 this type which is adapted to perform the necessary functions, although it will be understood that other forms of mechanical control apparatus may be employed.

In Fig. 2, the operating mechanism OM 75 is similar to that hereinbefore described, except that the several valves "Off-slow", "Off-fast", "On-slow" and "On-fast" are of somewhat modified construction, although of a type that is old and familiar in 80 the art, and, moreover, said valves are respectively actuated mechanically by means of manually operated handles 25, 26, 27 and 28 and suitable interconnecting rods 29, 30, 31 and 32. No description of the valve 85 is deemed necessary because of their well-known type of construction, it being considered sufficient to state that they are normally held in their initial positions by means of springs 33 and are so constructed 90 as to correspond, in function, to the valves described in connection with Fig. 1. By manipulating the proper operating handles 25, 26, 27 and 28, the respective valves may be caused to occupy positions correspond- 95 ing to those of the valves set forth in connection with Fig. 1 and, therefore, the same operating characteristics of the fluid-pressure mechanism OM may be secured, whereby movements at different rates of speed 100 may be effected in either direction or the piston 5 may be held stationary in any position.

In order to provide for concurrent operation of a plurality of fluid-pressure mechanisms similar to OM, bell crank levers 35, 36, 37 and 38 and actuating rods 39, 40, 41 and 42 are provided and these devices are so associated together and with the actuating rods 29, 30, 31, and 32 that the movement of the latter rods is transmitted to former ones, which serve to similarly and concurrently actuate other operating mechanisms OM with which they are mechanically associated. 115

Reference may now be had to Fig. 3, in which the system shown comprises a plurality of supply-circuit conductors 40^a, 41^a, and 42^a for delivering energy through an electrically operated line switch LS to the 120 primary windings P of a polyphase induction motor M having secondary windings S that are connected to a regulatable resistance device or liquid rheostat LR by means of which the acceleration of the motor M is 125 controlled.

The liquid rheostat LR comprises a tank 44 having a central bottom opening 45 and a movable tubular combined discharge and regulating valve 46, comprising an upper 130

portion 47 of a diameter less than that of the discharge opening 45 and a lower portion 48 of substantially the same diameter as the discharge opening and adapted to have a 5 running fit with the edge thereof. In the position shown in the drawing, the discharge opening 45 is open to permit the discharge of electrolyte which is continuously supplied to the rheostat tank 44 through an inlet 10 opening 49. However, if the regulating valve 46 be raised until the lower portion 48 of larger diameter just fills the discharge opening 45, then the continuously supplied electrolyte rises within the tank 44 to a level 15 corresponding to the top of the upper portion 47 of the valve 46. This height is termed the "Flush-level" and just immerses the lower ends of a plurality of electrodes 50^a, 51^a, and 52^a to which the secondary 20 windings S of the motor M are connected. When the regulating valve 46 is raised above its "Flush-level" position, the height of the electrolyte is correspondingly increased. It is clear, therefore, that the operation of the 25 motor M may be readily governed, at the will of the operator, by varying the height of the combined discharge and regulating valve 46 to suit the desired conditions of operation.

30 In order to permit the operator to control the actuation of the regulating valve 46, a fluid-pressure operating mechanism OM, which is similar in all respects to that described in connection with Fig. 1 is provided, the disposition, construction and operation of the several magnet valves "Off-slow," "Off-fast," "On-slow," and "On-fast" being identical to those hereinbefore described. In addition, a pneumatic or pressure 35 interlocking switching device PI is provided, which is associated with the upper end of the cylinder 4 and comprises a cylinder 50, a piston 51 contained therein and adapted to be actuated in an upward direction in opposition to a spring 52, in accordance with the pressure existing in the upper end of said cylinder. Associated with the piston 51 is a switch member 53 which is adapted to make co-operative engagement 40 with a pair of stationary contact terminals 54 when said piston is held in its uppermost position. The co-operative engagement of the switch members 53 and 54 is maintained only as long as the fluid pressure in the cylinder is greater than a predetermined value.

45 For the purpose of governing the operation of the several electrically operated magnet valves, an auxiliary interlocking controller IC is employed which embodies a plurality of stationary contact terminals 60 to 67, inclusive, that are adapted to make co-operative engagement with the conducting segments 68, 69 and 70, upon the position-indicating lines marked "Off," "Flush-

level," "Regulating" and "Short-circuit." The several movable conducting segments 68, 69 and 70 are conveniently mounted upon a carrier 72 which is biased to the "Regulating" position by means of a pair of oppositely disposed springs 73 and 74, although 70 movements in either direction may be effected in opposition to the one or the other of said springs.

The carrier 72 is provided with a plurality of projecting members or lugs 75 and 76 75 that are adapted to be engaged by an arm 77 which is attached to a rod 78 that connects the movable piston 5 with the regulating valve 46. The arm 77 and the lugs 75 and 76 are so arranged that the co-operative 80 engagement thereof is effected in predetermined positions of the regulating valve 46, whence the movements of the conducting segments 68, 69 and 70 are effected only in accordance with the actuation of the piston 85 5 and associated regulating valve 46. For instance, in the position shown in the figure, the carrier 72 and the movable conducting segments 68, 69 and 70 are held in their lowermost positions by reason of the engagement of the arm 77 with the lug 75, it being noted that the regulating valve 46 occupies its lowest position to permit the discharge 90 of electrolyte from rheostat LR. Under these conditions, the stationary contact terminals 60 to 67, inclusive, engage the conducting segments upon the position-indicating line marked "Off," and the centralizing spring 74 is held under compression.

If the regulating valve 46 be raised to 100 close the discharge opening 45 and to establish the "Flush-level" of the electrolyte, the arm 77 is raised to occupy the position shown in dotted lines A, and thus permits the spring 74 to raise the interlocking controller IC to its position marked "Flush-level."

As soon as the regulating valve 46 is raised above the "Flush-level" position, the spring 74 moves the interlocking controller 110 IC to its center or neutral position marked "Regulating," in which position it remains until the regulating valve 46 just reaches its uppermost position, when the arm 77 engages the lug 76 and moves the controller 115 IC to its position marked "Short-circuit" in opposition to the spring 73. The arm 77 then occupies the position shown in dotted lines B. In the "Short-circuit" position, connections are established for energizing 120 switches X and Y which are adapted to short-circuit the liquid rheostat LR and to eliminate all resistance from the secondary windings S of the motor M.

Referring now to Fig. 4, which illustrates 125 the control circuits for governing the operation of the apparatus shown in Fig. 3, the system shown embodies a master controller

MC' which comprises a plurality of stationary contact terminals 80, 81, 82, 83 and a coöperating movable conducting segment 84 that is adapted for engagement with stationary terminals in the positions marked "Lower", "Hold" and "Raise".

The line switch LS is provided with a plurality of interlock switches 85 and 86 and is operated by an electro-magnet 87, 10 while the short-circuit switches X and Y are provided with energizing coils X' and Y'.

Assuming the apparatus and circuit connections to be as shown in Figs. 3 and 4, the 15 operation of the system is as follows:

In order to accelerate the motor M, it is first necessary to establish a "Flush-level" 20 of the electrolyte within the rheostat LR in order to immerse the tips of the electrodes 50^a, 51^a and 52^a. To accomplish this result, the master controller MC' may be moved 25 into any of its operative positions, preferably to its position marked "Lower", in which a circuit is established from an auxiliary 30 source of energy or battery B which includes contact terminal 80, conducting segment 84, contact terminal 83 and conductor 90, where the circuit divides, one branch traversing the energizing coil of 35 valve magnet "On-fast" and conductor B— to the battery, and the other branch traversing conductor 91 to contact terminal 63 of the interlock controller IC and thence through the movable conducting segment 69 40 and, in parallel, the contact terminals 62, 64, and 65 and the respective energizing coils of valve magnets "On-slow", "Off-slow" and "Off-fast" to the B—conductor.

Thus, all of the valve magnets are 45 energized, and their respective valves are actuated into their opposite positions, whereby operating fluid is admitted beneath the piston 5 and is permitted to rapidly escape through the exhaust ports of both of the 50 magnet valves "Off-slow" and "Off-fast". The rapid reduction of pressure above the piston 5 quickly establishes a sufficient unbalancing to cause said piston and its associated combined discharge and regulating 55 valve 46 to be promptly raised in position. The operation of the operating mechanism OM, therefore, is quickly responsive to the manipulation of the master controller MC', and the time element of operation is reduced to a minimum.

As soon as the upward movement of the piston 5 and valve 46 is started, the spring 74 actuates the interlock controller IC and effects the engagement of contact terminals 66 and 67 with the conducting segment 70, 60 whereby a circuit is completed from conductor 90, which includes the energizing coil 87 of the line switch LS and contact terminals 66 and 67 which are bridged by

the conducting segment 70, to the B—conductor. Thus, the coil 87 of the line switch LS is energized, and said switch is closed to supply energy from the supply circuits 40^a, 41^a, and 42^a to the primary windings P of the motor M.

As a result of closing the line switch LS, its interlock switches 85 and 86 are also closed, but, inasmuch as the master controller MC' is assumed to occupy its "Lower" position, no additional circuits are 75 established. Furthermore, by reason of the reduction in pressure within the upper end of cylinder 4, the spring 52 of the pressure interlock PI serves to actuate the piston 51 and to lower the switch member 53 from its 80 coöperating stationary contact terminals 54. However, inasmuch as the master controller MC' still occupies its "Lower" position, this action has no effect upon the operation of the system. The purpose of the pressure 85 interlock PI will be hereinafter fully set forth.

Just prior to the attainment of the "Flush-level" position, contact terminals 64 and 65 of the controller IC become disengaged from the conducting segment 69 and the energizing coils of the valve magnet "Off-fast" and "Off-slow" are deenergized to permit said valves to return to their initial positions in which the exhaust ports 90 of both valves are closed and the inlet port of the valve "Off-slow" is opened. Hence, operating fluid is admitted to the operating cylinder 4 to balance that in the lower end thereof and to arrest the movement of the 100 piston 5 and associated discharge and regulating valve 46.

The movement of the valve 46, therefore, is arrested in its "Flush-level" position, and the continuously inflowing electrolyte rises 105 to that level and completes the secondary circuit of the motor M, after which the motor starts into operation in accordance with well-known principles.

If it be desired to further accelerate the 110 motor M, it is only necessary to move the master controller MC' to its "Raise" position in which the following additional circuits are completed,—one from conducting segment 84, which includes contact terminal 81, conductor 96, interlock switch 85 and conductor 97, where the circuit divides, one branch including coöperating switch members 53 and 54 of pressure interlock PI 115 which occupies its closed position, by reason of the full pressure of operating fluid in the upper end of cylinder 4, and, thence, through the energizing coil of valve "Off-fast" to the B—conductor, and the other branch including contact terminal 64 and the energizing coil of the valve magnet "Off-slow" to the conductor B—. The other circuit completed in the "Raise" position of the 120 125

master controller 'MC' includes contact terminal 82, conductor 93, interlock switch 86 and conductor 94 to a point intermediate the contact terminal 62 and the energizing coil 5 of valve magnet "On-slow".

- The magnet valves "Off-fast" and "Off-slow" are, therefore, energized and actuated to open their respective exhaust ports and to close the inlet port of the latter valve, where-
 10 by a rapid reduction in pressure of the operating fluid in the upper end of cylinder 4 is permitted which results in a quick movement of the piston 5 and the discharge and regulating valve 46 which responds substantially instantaneously to the manipulation of the controller.

As soon as the pressure in the upper end of the cylinder has been reduced to a predetermined amount, which immediately follows
 20 the initial movement of the piston 5, the pressure interlock device PI effects the disengagement of its coöperating switch members 53 and 54, and the valve magnet "Off-fast" becomes deenergized and its exhaust port closed. Thus, the escape of operating fluid is materially retarded, being confined to the single exhaust port of valve "Off-slow" which is of relatively small area. Therefore, after having effected a prompt response
 25 of the operating mechanism OM to the controller MC', the rapidity of movement of the piston 5 and discharge and regulating valve 46 is immediately retarded and further movements thereof are effected at a
 30 relatively slow rate.

When the valve 46 is raised above its "Flush-level" position, interlock controller IC is actuated into its "Regulating" position by spring 74, and contact terminals 62 and
 40 63 are disengaged from segment 69. The further regulation of the operating mechanism and valve 46 is independent of the controller IC which occupies its central position.

The upward movement of the piston 5 and
 45 valve 46 may be arrested in any desired position merely by moving the master controller MC' to its "Hold" position, whereby the contact terminal 81 becomes disengaged from conducting segment 84 and, hence, both
 50 of the magnet valves "Off-slow" and "Off-fast" are deenergized. Thereupon, said valves return to their initial positions, and balanced pressure conditions, acting upon the piston 5, are restored and said piston is
 55 held stationary.

In order to reduce the speed of operation of motor M, the master controller MC' may be moved to its position marked "Lower", whereupon contact terminal 82 is also dis-
 60 engaged from conducting segment 84, and the energizing coil of valve magnet "On-slow" is also deenergized. Thus, the "On-slow" valve returns to its initial position to cut off the supply of operating fluid to the lower end of the cylinder 4 and to open its

relatively small exhaust port, it being understood that the exhaust port of the valve magnet "On-fast" is still closed, and that operating fluid is admitted above the piston 5. Under these conditions, unbalanced 70 pressures obtain, and the piston 5 and associated discharge and regulating valve 46 are moved in a downward direction at relatively slow speed, thus permitting the excess of electrolyte within the rheostat LR to overflow and be discharged through the valve 46, whereby the level of electrolyte is lowered and the speed of the motor correspondingly reduced. Obviously, the lowering operation may be arrested in any position by moving the master controller MC' to its "Hold" 80 position.

For purposes of explanation, however, it will be assumed that the "Lower" position of the master controller is maintained, 85 in which case the downward movement of the piston 5 and valve 46 continues until contact terminals 62 and 63 are brought into engagement with the conducting segment 69 of the interlock controller IC between its 90 positions marked "Flush-level" and "Regulating". Thereupon, the valve magnet "On-slow" is also energized from conductor 91 through contact terminals 62 and 63, which are bridged by the conducting segment 69. 95 The magnet valve "On-slow", therefore, is caused to open its inlet port to admit operating fluid, whereby balanced pressures are obtained which serve to arrest the downward movement of the piston 5 and valve 100 46 in their "Flush-level" positions.

Assuming now that the master controller occupies its "Raise" position and that an upward movement of the piston 5 and valve 46 is effected at a slow rate until substantially the uppermost position thereof is reached, then the arm 77, which is associated with the connecting rod 78, engages the lug 76 on the carrier 72 and raises the interlock controller IC into its "Short-circuit" 110 position in opposition to the spring 73. In this position, conducting segment 68 bridges contact terminals 60 and 61 and completes a circuit from conductor 90 through the energizing coils X' and Y' of 115 the short-circuit switches X and Y, which results in the energization of said switches and their closure to establish short-circuit connections across the secondary windings S of the motor M. The motor M, therefore, 120 is operated at its full speed.

In order to disconnect the motor M from the supply circuits 40^a, 41^a and 42^a at any time and under any conditions of operation, the master controller MC' is moved to its 125 "Off" position to deenergize all of the magnet valves "Off-slow", "Off-fast", "On-slow" and "On-fast", whereupon said valves are permitted to assume their initial positions, as shown in Fig. 3, and hence, the piston 130

and associated discharge and regulating valve 46 are rapidly lowered to their initial lowermost positions. Thus, the electrolyte within the rheostat LR is rapidly discharged and the line switch LS is opened to disconnect the motor M from the supply circuits 40^a, 41^a and 42^a.

Obviously, my invention is not restricted to the specific circuit connections and arrangement and location of parts shown and described and to the mode of operation set forth, and modifications therein which do not depart from the spirit and scope of my invention are intended to be covered by the appended claims.

I claim as my invention:

1. The combination with a fluid-pressure operating device comprising a cylinder, a movable piston therein, and means comprising a plurality of valves directly connected to said cylinder for controlling the admission and release of operating fluid to and from the opposite ends of said cylinder and adapted to effect different rates of movement of said piston, of means for governing said controlling means.

2. The combination with a fluid-pressure operating device comprising a cylinder, a movable piston therein, and means associated with said cylinder for controlling the admission and release of operating fluid to and from the opposite ends of said cylinder, of remote-control means under the control of the operator for governing said controlling means to effect movements of said piston at different rates of speed.

3. The combination with a fluid-pressure operating device comprising a cylinder, a movable piston therein and a plurality of valves associated with each end of said cylinder for controlling the admission and release of operating fluid to and from the respective ends thereof, of means for governing the operation of said valves to cause said piston to move at different rates of speed.

4. The combination with a fluid-pressure operating device comprising a cylinder, a movable piston therein and a plurality of valves associated with each end of said cylinder for controlling the admission and release of operating fluid to and from the respective ends thereof, of means for governing the operation of some or all of said valves for causing said piston to be moved at relatively different rates of speed.

5. The combination with a fluid-pressure operating device comprising a cylinder, a movable piston therein, an inlet port associated with one end of said cylinder and a plurality of exhaust ports associated with the other end thereof, of means for governing said ports to effect movements of said piston at different rates of speed.

6. The combination with a fluid-pressure

operating device comprising a cylinder, a movable piston therein and an inlet port associated with one end of said cylinder and a plurality of exhaust ports associated with the opposite end thereof, of means for opening said inlet port and one of the oppositely located exhaust ports to effect slow movements of said piston and for opening said inlet port and a plurality of said oppositely located exhaust ports to effect relatively rapid movements of said piston.

7. The combination with a fluid-pressure operating device comprising a cylinder, a movable piston therein, a plurality of normally closed exhaust ports and a normally open inlet port associated with one end of said cylinder and a plurality of normally open exhaust ports and a normally closed inlet port associated with the other end of said cylinder, of means for governing said port to effect movements of said piston at different rates in either direction of operation.

8. The combination with a fluid-pressure operating device, comprising a cylinder, a movable piston therein, an inlet port in one end of the cylinder, and a plurality of exhaust ports of different sizes associated with the other end thereof, of manually operated means for controlling said ports to effect movements of said piston at different rates of speed.

9. The combination with a fluid-pressure device comprising a cylinder, a movable piston contained therein and means associated with the respective ends of said cylinder for governing the admission and release of operating fluid to and from said cylinder, of electrical means for controlling the operation of said fluid-controlling means to effect movements of said piston at different rates of speed.

10. The combination with a fluid-pressure device comprising a cylinder, a movable piston contained therein and a plurality of valves associated with the respective ends of said cylinder for governing the admission and release of operating fluid thereto and therefrom, of electromagnetic means under the control of an operator for governing the operation of said valves to effect different rates of movement of said piston.

11. The combination with a fluid-pressure device comprising a cylinder, a movable piston contained therein and a plurality of electromagnetically operated valves associated with the respective ends of said cylinder for governing the admission and release of operating fluid thereto and therefrom, of a remotely located master switch, and electrical means between said switch and said electromagnetically actuated valves for controlling the operation thereof to effect movements of said piston at different rates of speed.

12. The combination with a fluid-pressure device comprising a cylinder, a movable piston contained therein, an inlet valve and a plurality of exhaust valves associated with each end of said cylinder, of electrically controlled means for opening one of the inlet valves and one or both of the oppositely disposed exhaust valves for respectively effecting movements of said piston at slow and fast rates of speed in either direction of operation. 65
13. The combination with a fluid-pressure device comprising a cylinder, a movable piston contained therein, an inlet valve associated with one end of the cylinder, and a plurality of exhaust valves associated with the other end thereof, of electromagnetically controlled means for opening the inlet valve and one of the oppositely disposed exhaust valves for effecting movements of the piston and for opening said inlet valve and both of the oppositely located exhaust valves for effecting movements of said piston at a relatively rapid rate. 70
14. The combination with a fluid-pressure device comprising a cylinder, a movable piston contained therein and a combined inlet and exhaust valve and an auxiliary exhaust valve associated with each end of said cylinder, of electromagnetic means for governing the operation of said valves for effecting movements of said piston in either direction of operation at different rates of speed. 75
15. The combination with a fluid-pressure device comprising a cylinder, a movable piston contained therein and an inlet valve and a plurality of exhaust valves of different sizes associated with each end of said cylinder, of electromagnetic means for controlling the operation of said valves and for opening an inlet valve and one of the oppositely disposed exhaust valves, whereby the piston is moved at a predetermined rate and for opening an inlet valve and both of said oppositely disposed exhaust valves to effect similar movements of said piston at a relatively rapid rate. 80
16. The combination with a fluid-pressure operating device comprising a cylinder, a movable piston contained therein and a plurality of electromagnetically operated valves for governing the admission and release of operating fluid to and from said cylinder, of a master controller and circuit connections for governing the operation of said valves, and an auxiliary interlocking controller for adjusting the circuit connections of said valves to effect relatively different rates of movement of said piston. 85
17. The combination with a fluid-pressure operating device comprising a cylinder, a movable piston contained therein and a plurality of electromagnetically operated valves for governing the admission and release of operating fluid to and from said cylinder, of an auxiliary controller actuated by said piston, a master controller, and circuit connections between said master controller, said auxiliary controller and said valves for governing the operation of said valves to effect different rates of movement of said piston in either direction of operation. 90
18. The combination with a fluid-pressure operating device comprising a cylinder, a movable piston contained therein and a plurality of electromagnetically operated valves for governing the admission and release of operating fluid to and from said cylinder, of manually controlled means for governing the operation of said valves, and an auxiliary interlocking controller actuated by said piston for adjusting the circuit connections of said valves to effect different rates of movement of said piston during different portions of the travel thereof. 95
19. The combination with a fluid-pressure operating device comprising a cylinder, a movable piston contained therein and a plurality of electromagnetically operated valves for governing the admission and release of operating fluid to and from said cylinder, of manually controlled electrical means for governing the operation of said valves, and an auxiliary controller biased to an intermediate position and adapted to coöperate with said piston for interlocking said electrical governing means to control the operation of said valves, whereby said piston is moved at different rates through predetermined different portions of its travel. 100
20. The combination with a fluid-pressure operating device comprising a cylinder, a movable piston contained therein and a plurality of electromagnetically operated valves for governing the admission and release of operating fluid to and from said cylinder, of a master controller and circuit connections for governing the energization of said valves, an auxiliary interlocking controller, and means for biasing said controller to an intermediate position, said controller being actuated in opposition to said biasing means by said piston and adapted to rearrange the circuit connections of said valves in different positions of said piston. 105
21. The combination with a fluid-pressure operating device comprising a cylinder, a movable piston contained therein and a plurality of electromagnetically operated valves for governing the admission and release of operating fluid to and from said cylinder, of manually controlled means for governing the operation of said valves and effecting different rates of movements of said piston during different portions of the travel thereof in either direction. 110
22. The combination with a fluid-pres-

- sure operating device comprising a cylinder, a movable piston contained therein and a plurality of electromagnetically operated valves for governing the admission and release of operating fluid to and from said cylinder, of manually controlled electrical means for governing the operation of said valves, and auxiliary interlocking means co-operating therewith for effecting an initial 5 rapid rate of movement of said piston and, subsequently, a relatively slow rate of movement thereof.
23. The combination with an operating device comprising a cylinder, a piston movable therein, a plurality of normally closed exhaust valves and a normally open inlet valve associated with one end of said cylinder, and a plurality of normally opened exhaust valves and a normally closed inlet 10 valve associated with the other end thereof, whereby said piston is biased to its initial position, of electromagnetic means for actuating said valves, and controllable means for actuating all of said valves to their opposite 15 positions, whereby said piston is moved in one direction at a rapid rate and for subsequently actuating all but said first exhaust valve to their opposite positions for effecting a relatively slow movement of said piston.
24. The combination with a fluid-pressure operating device comprising a cylinder, a movable piston contained therein, and electromagnetically actuated valves for governing the admission and release of operating 20 fluid to and from said cylinder, of a master switch having three operating positions for governing the energization of said valves, whereby said piston is moved in either direction or held stationary at any point in its 25 travel, and an auxiliary controller co-operating with said master switch and said valves for varying the rate of movement of said piston during its travel.
25. The combination with a fluid-pressure operating device comprising a cylinder, a movable piston contained therein, and electromagnetically actuated valves for governing the admission and release of operating fluid to and from said cylinder, of electrical means embodying a master controller 30 for governing the operation of said valves to effect movements of said piston in either direction and to arrest its movement in any position, and an interlocking controller adapted to be actuated by said piston for governing the energization of said valves whereby said piston is moved at relatively 35 different rates during different portions of its travel in either direction of operation.
26. In a control system, the combination with a dynamo-electric machine and a liquid rheostat for governing the acceleration of said machine and having a movable tubular regulating valve adapted to be 40 raised and lowered to fix the height of electrolyte, of means for actuating said regulating valve and comprising a cylinder, a movable piston and a plurality of electrically operated valves associated with said cylinder, and electrical means for controlling the operation of said machine and embodying a master switch and an interlocking controller for governing the energization of said valves and effecting a rapid initial movement of said piston and associated regulating valve and a subsequent 45 relatively slow movement thereof.
27. In a control system, the combination with a dynamo-electric machine, a liquid rheostat for governing the acceleration of said machine and having a bottom discharge opening, and a tubular regulating valve disposed therein and adapted to be raised to close said opening and to fix the height of the electrolyte, of a fluid-pressure operating mechanism comprising a cylinder, a movable piston contained therein and a plurality of electrically operated valves associated therewith for governing the admission and release of operating fluid to and from said cylinder, and control means for governing the operation of said machine by causing said valves to effect an initial relatively rapid movement of said regulating valve to close said discharge opening and a subsequent slow movement thereof for regulating the height of said electrolyte.
28. In a control system, the combination with a dynamo-electric machine, a liquid rheostat for governing the acceleration of said machine and having a bottom discharge opening, and a tubular regulating valve disposed therein and adapted to be raised to close said opening and to fix the height of the electrolyte, of a fluid-pressure operating mechanism comprising a cylinder, a movable piston contained therein and a plurality of electrically operated valves associated therewith for governing the admission and release of operating fluid to and from said cylinder, manually operated control means, and an auxiliary interlocking controller adapted to be actuated by said piston for conjointly governing the operation of said machine by causing the actuation of said cylinder valves to effect an initial rapid movement of said piston and associated regulating valve for closing said discharge opening and for subsequently permitting relatively slow movements thereof in either 100 direction of operation.
29. The combination with a cylinder, a movable piston therein, an electrically operated inlet valve associated with one end thereof, and a plurality of electrically operated exhaust valves associated with the other end thereof, of electrical means for causing said valves to be moved into their 105 110 115 120 125

- open positions, and a fluid-pressure interlocking switch for governing the operation of one of said exhaust valves, said fluid-pressure switch being associated with said cylinder and adapted to deenergize said exhaust valve under predetermined conditions of pressure in said cylinder. 5
30. The combination with a cylinder, a movable piston therein, means for admitting operating fluid to one end of said cylinder, and a plurality of electrically operated exhaust valves associated with the other end thereof, of an interlocking switching device adapted to complete the circuit of one of 10 said electrically operated exhaust valves under full-pressure conditions and for deenergizing said exhaust valve to effect the closure thereof under predetermined minimum-pressure conditions. 15
- 20 31. The combination with a cylinder, a movable piston contained therein, a normally closed electrically operated inlet valve associated with one end of said cylinder, a normally open electrically operated inlet 25 valve and a plurality of normally closed electrically operated exhaust valves associated with the other end of said cylinder, whereby said piston is biased to its initial position, and means for energizing said 30 valves to effect movements thereof into their opposite positions, whereby said piston is actuated rapidly in one direction, and a pressure-actuated interlocking switch normally in circuit with one of said electrically 35 operated exhaust valves under full pressure conditions for deenergizing said valve and effecting its closure under predetermined reduced-pressure conditions, whereby the rate of movement of said piston is reduced. 40
- 40 32. The combination with a cylinder, a movable piston contained therein, and means for admitting operating fluid to one end of said cylinder, of an electrically operated exhaust valve associated with the other end 45 thereof and adapted to be closed when deenergized, an interlocking switch dependent upon the pressure of the fluid within the end of the cylinder with which said exhaust valve is associated and adapted to complete 50 a circuit through said electrically operated exhaust valve under normal-pressure conditions and to interrupt said circuit under reduced-pressure conditions. 55
33. The combination with a fluid-pressure operating device comprising a cylinder and a movable piston, of electrically operated valves associated with said cylinder for governing the admission and release of operating fluid thereto, and means for governing 60 the operation of one of said electrically operated valves in accordance with pressure conditions. 65
34. The combination with a fluid-pressure operating device comprising a fluid-contain- 70 ing member and a movable member disposed therein, of a controllable valve associated with said fluid-containing member and means for governing the operation of said valve in accordance with pressure conditions within said fluid-containing member. 75
35. A fluid-pressure operating device comprising a cylinder, a movable piston, and an inlet valve and a plurality of exhaust valves associated with each end of said cylinder for respectively governing the admission and release of operating fluid to and from said cylinder. 80
36. The combination with a fluid-pressure device comprising a cylinder, and a movable piston therein, of an inlet valve associated with one end of said cylinder, a plurality of exhaust valves associated with the other end thereof, and means controlled by said piston for governing the operation of said valves. 85
37. The combination with a fluid-pressure device comprising a cylinder, and a movable piston therein, of means for admitting operating fluid into one end of said cylinder and a plurality of exhaust valves associated with the other end thereof for controlling the rate of movement of said piston. 90
38. The combination with a fluid-pressure device comprising a cylinder, and a movable piston therein, of an inlet valve, a plurality of exhaust valves associated with each end of said cylinder, and means controlled by said piston for governing the operation of said valves. 95
39. The combination with a fluid-pressure device comprising a cylinder, and a movable piston therein, of an electromagnetically operated combined inlet and exhaust valve and an electromagnetically operated auxiliary exhaust valve associated with each end 100 of said cylinder for effecting movements of said piston in either direction at different rates. 105
40. The combination with a fluid-pressure device comprising a cylinder, and a movable piston therein, of a plurality of electrically operated valves associated with one end of the cylinder for governing the admission and release of operating fluid thereto and therefrom, and a pressure-responsive device 110 also associated with the same end of said cylinder. 115
41. The combination with a fluid-pressure device comprising a cylinder, and a movable piston therein, of means for admitting fluid pressure into one end of said cylinder, and a normally open inlet valve and a plurality of normally closed exhaust valves associated with the other end of said cylinder for effecting different rates of movement of said 120 piston. 125
42. The combination with a fluid-operated device comprising a cylinder and a

- movable piston, of means for effecting a predetermined normal movement of said piston, and means cooperating with said first means to effect a relatively rapid initial movement of said piston.
43. The combination with a movable member, of fluid-pressure means for effecting a predetermined normal movement of said member, and means for initially accentuating predetermined unbalanced-pressure conditions to effect a relatively rapid initial movement of said member.
44. The combination with a movable member, of operating means therefor normally biased to a predetermined position, means for reversing the biasing action to effect normal movement of said member, and means acting during the reversal to permit a relatively rapid movement of said member.
45. The combination with a movable member, of means actuated by predetermined unbalanced fluid-pressure conditions to effect normal movements of said member, and means associated with said actuated means for initially permitting a relatively rapid unbalancing of certain fluid-pressure conditions to effect a correspondingly rapid initial movement of said member.
46. The combination with a fluid-containing cylinder and a movable piston disposed therein, of means for effecting a predetermined normal movement of said piston, and means for accelerating said movement during a predetermined initial portion of the piston travel.
47. The combination with a fluid-containing cylinder and a movable piston disposed therein, of means for effecting a predetermined normal movement of said piston, and means acting in conjunction with said first means for effecting an initial relatively rapid movement of said piston during a predetermined portion of its travel.
48. The combination with a fluid-containing cylinder and a movable piston disposed therein, of means for effecting a predetermined normal movement of said piston, and means dependent upon the position of said piston for effecting a relatively rapid movement thereof.
49. The combination with a member to be actuated and a fluid-pressure operating device for actuating said member, of means associated with said operating device and dependent upon the position thereof for effecting an initial rapid movement of said member to be actuated.

In testimony whereof, I have hereunto subscribed my name this 25th day of Nov. 1914.

ARTHUR J. HALL.
